ROBERT HENEAGE, GEORGE MILSOM, AND HENRY SPENDELOW, OF
BUFFALO, NEW YORK.

Letters Patent No. 61,554, dated January 29, 1867.

IMPROVEMENT IN COMBINED PULLEY AND CABLE.

The Schedule referred to in these Letters Patent and making part of the same.

TO ALL WHOM IT MAY CONCERN:

Be it known that we, ROBERT HENEAGE, GEORGE MILSOM, and HENRY SPENDELOW, of the city of Buffalo, in the county of Erie, and State of New York, have invented certain new and useful improvements in Bands and Belts for communicating motion; and we do hereby declare that the following is a full and exact description thereof, reference being had to the accompanying drawings, making part of this specification, in which—

Figure 1 is a view in elevation representing our improvements.

Figure 2 is a detached view of a pulley with our improved wire cable, a portion of the pulley being shown as broken away to show its construction.

Figure 3 is a side or face view of a wheel provided with our improved iron belt.

Like letters of reference designate corresponding parts in all the figures.

The nature of our invention consists in the construction of driving-belts, for machinery, of annealed iron, rolled, drawn, or hammered to the required thinness, as a substitute for the ordinary materials, such as leather, rubber, &c., and it further consists in the employment of wire cables in combination with a grooved-faced pulley, said groove being provided with a suitable flexible or partially elastic filling for increasing the adhesion thereof.

As represented in the drawings, fig. 1 shows the application of these improvements in both forms to a purpose which presents the most serious difficulties, as regards the situation and use of belts for communicating power, viz, to driving the buckets of a grain elevator, A A being the upright wooden frame; B is a driving-shaft provided with two driving-pulleys C and D, in addition to the pulleys carrying the endless chain or cable to which are attached the buckets E E. The upper shaft has corresponding pulleys lettered respectively C' and D', and their shaft B'. The driving-belt G on pulleys C C' consists of a strip of thin malleable iron reduced, by rolling, drawing, or other suitable means, to that degree of thinness that it is sufficiently flexible and pliant to run on the surfaces of the pulleys which are usually and preferably of cast iron, but may be of other suitable material. The faces of these pulleys are uncovered, the metallic strip coming in direct contact therewith so that the natural adhesion of the metal surfaces will prevent slipping of the belt upon the wheel. We find by a series of practical experiments that the fibrous structure of a piece of ductile iron, when worked to that degree of compactness that results when reduced to thin sheet or strap, is specially adapted to adhere under slight pressure to the surface of cast iron having a porous and crystalline structure, and this quality peculiarly adapts it to the purpose of driving-pulleys for communicating motion and power, as the adhesion secures the friction necessary between the belt and pulley to prevent slipping. It has also the advantage of not accumulating gum or other foreign substance to interfere with its efficiency. It is well known that the friction and motion of running belts generate electricity, and this occurs equally, or to a greater extent, with our iron belt, and the electric condition of the belt greatly increases its adhesion to the pulley and thereby increases its efficiency. Where leather belts are employed in situations which expose them to a high temperature they are soon destroyed by the heat, while India rubber are rendered entirely useless by softening; exposure to wet and moisture also soon destroys the efficiency of leather and textile belts; while in these situations the iron belt has perfect immunity, working equally well in heat, cold, or wet. Our iron belting also is comparatively unaffected by the influence of acids and other chemicals which soon render worthless belting constructed of the ordinary materials. Its cost is much less than any other material for belts, and its durability exceeds all other substances which have been applied to the purpose, while it is lighter and requires a less expenditure of driving power in performing its work. Belts are often used in situations which expose them to the action of chemical liquids and vapors that are destructive to leather, India rubber, and textile materials, and in these cases our improved belts prove far more durable and effective. The modification, shown most clearly in fig. 2, is designed for those situations and purposes to which a cable is better adapted than a flat belt, and where it is not subjected to a high temperature and is designed to increase the adhesion between the band H and pulley D, which from the small surface of the two which come in contact, in consequence of the cable form, would be too slight for many purposes. The face of the pulley has turned in it a V-shaped groove which is filled with hardened India rubber, gutta percha, leather, or any suitable compound possessing a slight degree of elasticity to enable the cable to partially bed

itself therein. It should preferably sink half its diameter so that the converging sides of the groove or seat will compress somewhat the intervening substance *i*.

What we claim as our invention, and desire to secure by Letters Patent, is—

The combination of the wire cable H, with the grooved pulley D, and intervening packing *i*, constructed and operating substantially as described.

In witness whereof we have hereunto signed our names in the presence of two subscribing witnesses.

ROBT. HENEAGE,
GEORGE MILSOM,
HENRY SPENDELOW.
